UNITED STATES PATENT OFFICE.

JOHN H. GIBSON, OF BRUIN, PENNSYLVANIA.

BLADE SHARPENER.

Application filed October 23, 1925. Serial No. 64,433.

This invention relates to a device especially designed for sharpening razor blades, and aims to provide novel means whereby a number of blades may be supported within 5 a casing and held in such position to be engaged by a rotary sharpening member.

An important object of the invention is to provide a device of this character wherein the blades may be readily and easily removed 10 and positioned within the casing.

A further object of the invention is to provide a sharpening device wherein the pressure may be regulated by the operator while the device is in operation.

15 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention. 25

Referring to the drawing:

Figure 1 is a plan view of a sharpening device constructed in accordance with the invention.

30 Figure 2 is a transverse sectional view therethrough.

Figure 3 is a sectional view taken on line 3-3 of Figure 2.

Figure 4 is a sectional view taken on line 35 4-4 of Figure 2.

Figure 5 is a section through a modified form.

40 Referring to the drawing in detail, the device includes a circular casing indicated generally by the reference character 5 which may be constructed of any suitable material such as hard rubber or the like.

Secured within the casing is a base indicated by the reference character 6 which base 45 is formed preferably of soft rubber, the same being secured in position within the casing 5 in any suitable manner.

Extending upwardly from the central portion of the casing is a pin 7 that passes 50 through a central opening in the base 6, which pin is provided with a groove arranged adjacent to its upper end, for the reception of the spring 8 which is carried by the cap 9, so that the cap may be readily 55 and easily removed or positioned on the pin 7.

As illustrated by Figure 4, the base 6 is formed with a plurality of integral blade supports 10 which are formed with inclined upper surfaces to receive the blades 11 and support them at oblique angles with respect to abrading element, to be hereinafter more fully described.

Lugs 12 extend upwardly from the upper surfaces of the blade supports 10 and are 65 adapted to fit within the usual blade openings to secure the blades against movement while they are being sharpened.

Arranged adjacent to the lower edge of each blade supporting member 10 is an integral boss 13 which is provided with a groove 14 for the reception of one edge of the blade to the end that the blade will be held against tilting under the action of the abrading member. 70

The abrading member is indicated by the reference character 15 and includes a disk-like body portion formed with a central opening to permit the same to be positioned over the pin 7. 75

Secured to the under surface of the member 15 is a leather disk 16 which acts as a strop when rotated over the blades supported in the casing and which in the present showing are indicated by the reference character 11. 80

The disk or member 15 is rotated by means of the finger pieces 18 which are arranged adjacent to the central portion of the disk-like body portion 15 to the end that pressure may be directed to the body portion 15 by the operator, to accomplish the purpose of the invention. 90

As shown by Figure 5, the base 6 is cut away to accommodate blades such as indicated at 19, which blades have a reinforced backing 20. 95

It might be further stated that the blade supports have their upper surfaces curved at 21 providing a substantially thin supporting edge contacting with the under surface of the blade in such a way that the blade will be permitted to move slightly on its support to adjust itself and insure a true sharpening of the blade. 100

While I have shown and described an abrading member in the form of a leather disk, it is to be understood that another body portion such as shown at 15 may be used, the same having an abrading surface 110 formed of emery or the like for sharpening the blades. 105

In the use of the device, the blades are positioned in a manner as shown by Figure 2 and the member 15 positioned thereover, after which the member 15 may be rotated 5 causing the leather disk to rub the cutting surfaces of the blades to sharpen them.

I claim:—

1. A razor blade sharpening device embodying a circular casing having an upper standing flange, a flexible supporting member within the casing, said flexible supporting member having blade supports formed integral therewith, said blade supports having concaved upper surfaces and having 10 bosses formed with grooves to receive the edges of blades, to be sharpened and an abrading member rotatably mounted within the casing and adapted to engage blades supported therein.
- 20 2. A razor blade sharpener embodying a

casing, a removable flexible supporting member fitted within the casing, said supporting member having inclined supporting surfaces, lugs extending from the supporting surfaces and adapted to pass through openings of razor blades to secure the razor blades against movement, elastic bosses formed on the supporting member and having grooves to receive the edges of razor blades to prevent tilting of the razor blades 25 while they are being sharpened, and a rotary abrading member adapted to be operated over the supporting member to contact with the blades positioned on the supporting member to sharpen the blades.

In testimony that I claim the foregoing as my own, I have hereto affixed my signature.

JOHN H. GIBSON.
